GRANT SIPP, OF PATERSON, NEW JERSEY, ASSIGNOR TO SIPP EASTWOOD CORPORATION, OF PATERSON, NEW JERSEY, A CORPORATION OF NEW JERSEY

WARPING MACHINE

Application filed November 28, 1928. Serial No. 322,439.

This invention relates to warping machines and particularly to means for controlling the driver or other instrumentality for determining the rotation of the reel. In these machines the reel driver is usually shifted into driving contact with the reel by the operator through a shifter system including a lever engaged at one end with the driver and at the other end connected by a link with a treadle. One object of this invention is to provide means whereby when a predetermined yardage has been wound on the reel the shifter system may be rendered, preferably automatically, impotent or inoperative to bring the driver into or hold it in driving engagement with the reel, whereby the reel cannot be re-started and the yardage predetermined cannot thus be unwittingly exceeded until at least the operator has performed a resetting operation. When effected automatically, this is accomplished by a part which moves with the reel encountering another part to move the same and cause the shifter means to be rendered inactive as stated. Usually, either subject to the operator or automatic means, the cutting off of the power in this way will be practically instantaneously accompanied by a braking and stopping of the reel; wherefore, given means also included in the invention to re-establish the shifter system in operative state, another object is to construct such means so that the latter of said parts will clear and take a position relatively rearward of the former in the resetting operation. In the preferred form the means to check the reel is a brake which said system, when retracted so that the driver is not driving the reel, permits to act but which it renders inactive when said system is in the position where the driver is held in driving engagement with the reel; and a further object is, if the machine is equipped with means to lock said system in the position for driving the reel and therefore for maintaining the brake inactive, to construct the mechanism so that when said system is automatically rendered impotent or inoperative in the respects hereinbefore stated said system will be unlocked or released so that the brake will be set.

In the drawings,

Fig. 1 is a side elevation of a warping machine embodying the invention;

Fig. 2 is a fragmentary side elevation of the principal parts concerned in the invention;

Fig. 3 shows in elevation as seen from the right in Figs. 1 and 2, and partly in section, what is seen in Fig. 2;

Fig. 4 is a front-to-rear vertical fragmentary section showing principally the shifter system, the means for automatically rendering the same inactive, and the means for locking the treadle of said system in the position where said system (if otherwise effective) will keep the reel rotating;

Figs. 5 and 6 are detail sectional views on line 5—5, Fig. 2, with certain parts shown in different positions;

Fig. 7 is a detail sectional view on line 7—7, Fig. 2; and

Fig. 8 is a diagram illustrating the operation of the shifting means shown in the first four figures.

1 is the frame or supporting structure and 2 the reel journaled therein. 3 is a brake-strap engaging the rim 2^a of the reel and 4, 4^a known supporting means for the same. 5 is a sprocket-and-chain connection whereby from the reel a screw-shaft 6 for effecting the 50 traverse, parallel with the reel-axis, of the usual reed-carriage (not shown) is rotated. 7 is the mentioned driver rotated from any source by a belt 8 and normally by its weight held depressed and clear of the rim 2^a but 55 adapted to be raised to engage said rim, being here as usual journaled in a pivoted bracket 9.

The shifter system here includes an actuated member, an actuating member and 90 a toggle connection between them. The actuated member is a lever 10 fulcrumed between its ends, one end supporting the driver. The actuating member is here a pitman 11 having a crook-like upper end and having a 95 treadle 12 pivoted to its lower end and fulcrumed in the frame and further having means to limit its upward and downward movement, one of which is frame 1 with which a lug 13 on the treadle is held engaged 100

under the influence of a spring 14 connecting the treadle with the frame and the other of which is a stud 16 on the frame with which the upper end of a slot 15 in the pitman is adapted to engage (Figs. 4 and 8) under a condition to be stated. The said toggle connection includes links 17 within the crook of the pitman and pivoted together at 18, having their outer ends pivoted to the pitman and the lever, and having stops 17^a and 17^b which in the extended condition of the toggle engage each other (Fig. 4), the toggle being adapted to be broken or buckled by application of force against the same from the right in Fig. 4 and between the pivots where the connection is joined to the lever and pitman (a hump 11^a on the pitman crook may limit the buckling movement); a spring 19 connects the crook of the pitman with the lever and tends to maintain the toggle connection in either its extended or buckled condition.

When the shifter system is normal (i. e., its said connection being in extended state), under the pull of spring 14 and the weight of the driver it tends to stand in the full-line position shown by Fig. 8 or against the stop 1, the driver being then so spaced from rim 2^a that on depressing the pitman the driver will encounter the rim before stop 15 encounters stud 16, and so the reel will be driven. But if the system be collapsed by breaking the toggle the driver will assume the dotted line position; if this happens when it is being held by the system in contact with the rim it will clear it, so that the reel will cease to be driven, and if it happens when it is not in contact therewith (as when the driver is retracted, or not driving the reel, but the operator, as occasionally happens, should be turning the reel directly by hand) depressing the pitman in the effort to cause it to contact with the rim will be futile because the pitman will be checked by contact of 15 with 16 before the now increased space between the driver and rim has been overcome. In short, with the shifter system collapsed the reel cannot be restarted thereby in any case until the toggle connection is re-established in extended condition. Thus, assume the winding of the warp has proceeded to some predetermined extent, at which time the operator must attend to some matter in connection with the warp, as to cut off the portion already wound or introduce some marker, the inoperative state of the shifter system prevents further reeling by resort to the shifter system until said system has been reset.

It is known in the use of these machines to employ a chock to hold in active position a movable man-operated shifter system for a driver (as 7), as where said system comprises a lever (as 10), a treadle (as 12) and a simple link connecting the lever and treadle,

which chock the operator removes when the driving is to cease. According to one aspect of the invention it is not a matter of introducing a chock between such system and some support, as the frame, but of making said system itself collapsible, whereby when said system is in one of its collapsed and extended states it would hold the driver further from the reel than when said system is in its other state; in the present and preferred species of the invention said system is normally adapted to assume one of said states but releasably held thereagainst and when in such state it holds the driver further from said reel than when in the other state.

While, with notice obtained in some way that the winding has proceeded to a predetermined extent, the operator might by hand render said system thus inoperative to restart the reel so that its inoperative state would remain a reminder to attend to the matter requiring attention, I prefer to accomplish this automatically by tripping means: The frame includes a standard 1^a on a stud 20 of which is journaled a dial 21 which is driven by the reel through a shaft 22 which at one end is connected with shaft 6 by bevel gearing 23 and at the other end has a worm 24 meshing with worm-teeth on the dial. It will suffice to note that the dial has a stud or projection 25 which may be set, fixed thereto, at some position in a circle concentric therewith. A push-rod 26 affording a knock-off member is confined to slide lengthwise in the end of an arm 27 and is connected by a bell-crank lever 28 with a link 29 which is connected with the pivot 18 of the toggle-links. When the toggle is extended a roller 26^a on member 26 projects into the path of the stud 25, wherefore when the reel turns the dial around until this stud encounters said roller the consequent displacement of said member will cause the toggle to be broken, or the collapse of the shifter system.

In a certain aspect the toggle connection 17 acts as a withdrawable holding means or chock—for instance, when the operator is holding the link down (or has locked it down as will hereinafter appear) and consequently secured the lever in the position where the driver is against the reel—in which case the link 11 affords the support for the chock. As already indicated the use of withdrawable chock means in these machines to hold some means for controlling the movement of the reel (as a driver or it may be a brake) in the position where the reel may be driven is known. It is a new, however, to provide for automatic withdrawal of the chock means on motion of the driven means, including the reel, to a predetermined extent, and this I claim regardless of what form the chock means takes.

The resetting of the tripping means, and

here also of the toggle (since they are connected at 18 and form in effect a mechanism movable as a unit) may be accomplished by a lever 30 fulcrumed in the frame and having a handle 30^a upstanding in convenient reach when the operator is in position to start the reel by depressing treadle 12 and also having a cam arm 30^b to wipe against a stud 28^a on the bell-crank lever 28 when the handle is shifted to the right or as it appears in Fig. 3 (this lever, by the weight of the handle and cam arm, is normally held to the left, bearing against member 22). As will appear a device (as 33) normally tends to press on brake-band 3 to stop the reel, being however retracted whenever the treadle is depressed; the treadle will usually be released at once on breaking of the toggle (by the operator, if he is holding the treadle down, as soon as he 15 senses the break in the toggle, or by release of the treadle automatically if it is locked down as hereinafter stated), and this will leave the stud usually in a position precisely to interfere with the upward resetting movement of said member unless the latter were shifted laterally or substantially lengthwise and rearwardly of the path of the stud to clear the stud in such movement. To permit such shifting the arm 27 in which the 20 push-rod is guided is pivoted in standard 1^a and normally held to the right in Fig. 2, or against the standard, by a spring 31, and may be shifted to the left as an incident of the resetting operation by a cam 32^a on an arm 25 of lever 30 when the latter is shifted to reset the toggle, so that as the push-rod rises in the resetting it is displaced to the left and its roller therefore rises relatively back and thus clear of the stud 25.

40 The brake afforded by band 3 is so controlled that it is off when the reel is driven and on when the driver is withdrawn from the reel rim. Thus, as in my application Serial No. 317,650, there may be a lever 33 suitably fulcrumed on a structure 34 in effect forming a fixed part of the frame and normally urged against the brake-band 3 by a spring 35 but adapted to be retracted by having its depending arm 33^a connected with a link 36 which has an abutment at 36^a in the path of movement, when the treadle is depressed, of a staff-like crank 37 upstanding rigidly from the treadle 12, so that lever 33 is withdrawn when the treadle is depressed to start the reel. There may also be means to lock the treadle down so that the operator can leave the machine running alone, such means here being the same as in my said application and comprising (Fig. 4) a hand-bar 38 revoluble in the frame and having a crank 39 which is one element of a toggle connection between said shaft and the treadle, the other element of which is a link 40 which is pivoted to the crank at 40^a and has a slot 40^b (Fig. 1) receiving a stud 12^a on the treadle, the up-

per end of the link projecting upwardly beyond pivot 40^a and forming a bunter to impinge against the shaft when the shaft has been turned anti-clockwise in Fig. 4, or until pivot 40^a has passed a plane coinciding with the axis of the shaft and pivot 12^a (Fig. 3). With the machine so equipped, there should be means to cause collapse of this toggle-lock for the treadle when the toggle lock for the shifter means is collapsed, else the described connection between the treadle and lever 33 will not be released to apply the brake. Hence, a link 41 is connected to the pivot 40^a and has a slot 41^a receiving the pivot 18 of the toggle-links 17, and when the treadle lever is toggle-locked down the forward end of this slot is positioned so as to be engaged by the pivot 18 when the toggle-lock 17 is broken which acts through the link to break or collapse the treadle-lever toggle-lock. A slot (41^a) is present instead of a hole in the link so that the treadle-lever toggle-lock may be manipulated idly with respect to the other toggle-lock when the latter is normal or extended, and it is so formed that when the treadle-lever toggle-lock is operated to lock down the treadle it will not establish the toggle-lock at 17 (note the space in Fig. 4 between pivot 18 and the left-hand end of the slot), else the operator would have it in his power to reestablish the shifter system as an incident of the usual movement for starting the reel, as in the case where, as by perchance having rotated the reel somewhat by hand, the dial stud 25 was made to pass the push-rod and so no longer remained an obstacle to such re-establishment of the shifter system.

Having thus fully described my invention, what I claim is:

1. In a warping machine, the combination of the frame, driven means including a revoluble reel on which to wind the warp, a rotated driver for said means, and a collapsible shifter system movable by the operator to shift the driver into driving relation to said means, said system in one of its collapsed and extended states holding said member further from said means than when in the other state.

2. In a warping machine, the combination of the frame, driven means including a revoluble reel on which to wind the warp, a rotated driver for said means, a collapsible shifter system movable by the operator to shift the driver into driving relation to said means, said system in one of its collapsed and extended states holding said member further from said means than when in the other state, and means, actuated from the first means, to change said system from one to the other of its collapsed and extended states.

3. In a warping machine, the combination of the frame, driven means including a revoluble reel on which to wind the warp, a rotated driver for said means, and a shifter system movable by the operator to shift the

driver into driving relation to said means and including an actuated member, an actuating member and a toggle connection between said members.

5 4. In a warping machine, the combination of the frame, driven means including a revoluble reel on which to wind the warp, a rotated driver for said means, a shifter system movable by the operator to shift the driver into driving relation to said means and including an actuated member, an actuating member and a toggle connection between said members, and means, actuated from the first means, to shift said connection from one to the other of its collapsed and extended states.

10 5. In a warping machine, the combination of the frame, driven means including a revoluble reel on which to wind the warp, a rotated driver for said means, and a collapsible shifter system movable by the operator to shift the driver into driving relation to said means, said system being normally adapted to assume one of its collapsed and extended states but releasably held thereagainst and 15 when in said state holding the driver further from said means than when in the other state.

20 6. In a warping machine, the combination of the frame, driven means including a revoluble reel on which to wind the warp, a rotated driver for said means, and a collapsible shifter system movable by the operator to shift the driver into driving relation to said means, said system being normally adapted to assume one of its collapsed and extended 25 states but releasably held thereagainst and when in said state holding the driver further from said means than when in the other state, and means, actuated from the first means, to trip said system and thereby cause change 30 thereof from said state to the other state.

25 7. In a warping machine, the combination of the frame, driven means including a revoluble reel on which to wind the warp, means to control the movement of the first 40 means movable into but normally urged out of position where the first means may be driven, withdrawable chock means to hold the second means in said position, and means, actuated from the first means, to withdraw 45 the chock means on a predetermined motion of the first means.

50 8. In a warping machine, the combination of the frame, driven means including a revoluble reel on which to wind the warp, 55 means to control the movement of the first means movable into but normally urged out of position where the first means may be driven, toggle means forming a chock and in one of its extended and collapsed states holding the second means in said position, and means, actuated from the first means, to change the toggle means to its other state.

55 9. In a warping machine, the combination of the frame, a driven means including a revoluble reel on which to wind the warp, said

means having a projection, mechanism to be tripped including means to control the movement of the first means and being releasably held in but normally urged out of position where said first means may be driven, tripping means for said mechanism including a knock-off member normally projecting into the path of said projection but shiftable by the same out of such path, and means to reset the tripping means with said member in said path.

70 10. In a warping machine, the combination of the frame, a driven means including a revoluble reel on which to wind the warp, said means having a projection, mechanism to be tripped including means to control the movement of the first means and being releasably held in but normally urged out of position where said first means may be driven, tripping means for said mechanism including a knock-off member normally projecting into the path of said projection but shiftable by the same out of such path, and means to reset the tripping means with said member in said path, said member being shiftable substantially lengthwise of said path whereby to be brought to a position in said path rearward of the projection.

75 11. In a warping machine, the combination of the frame, a driven means including a revoluble reel on which to wind the warp, said means having a projection, mechanism to be tripped including means to control the movement of the first means and being releasably held in but normally urged out of position where said first means may be driven, tripping means for said mechanism including a knock-off member normally projecting into the path of said projection but shiftable by the same out of such path, and also shiftable substantially lengthwise thereof, and means to reset the tripping means with said member in said path and relatively rearward of the projection.

80 12. In a warping machine, the combination of the frame, driven means including a revoluble reel on which to wind the warp, a rotated driver for said means, collapsible means to hold the driver in driving relation to the driven means and including an actuator, a brake means normally urged into braking relation to the driven means but held retracted by the actuator when in the position where the collapsible means holds the driver in said relation, releasable means to hold the actuator in said position, and means, actuated from the driven means when in motion, to collapse said collapsible means, said collapsible means being thereupon adapted to release the releasable means.

85 In testimony whereof I affix my signature.
GRANT SIPP.
